UNITED STATES PATENT OFFICE.

CLYDE F. LANDAHL AND CARLOS H. LANDAHL, OF YOUNGSTOWN, OHIO.

NONGLARE HEADLIGHT.

Application filed November 19, 1921. Serial No. 516,414.

To all whom it may concern:

Be it known that we, CLYDE F. LANDAHL and CARLOS H. LANDAHL, citizens of the United States, residing at Youngstown, in the county of Mahoning and State of Ohio, have invented certain new and useful Improvements in Nonglare Headlights; and we do hereby declare the following to be a full, clear, and exact description of the same, reference being had to the accompanying drawings, forming part of this specification.

This invention relates to a headlight for use on automobiles and has for its particular object the provision of a simple and efficient device of that character that will prevent the objectionable glare usual in ordinary headlights which glare extends above the roadbed thus blinding the driver of an approaching machine.

In the drawings,—

Figure 1 is a front elevation of a preferred form of the device.

Fig. 2 is a horizontal section taken just above the level of the electric bulb and socket.

Fig. 3 is a vertical section taken just inside of the lens or pane.

Fig. 4 is a central vertical section taken at right angles to the plane of the front lens.

The outer casing 10 is about five-eighths of the usual size of a headlight, being bounded by a horizontal base 11 cutting off the lower three eighths of the ordinary headlight. The casing is provided with the usual sockets 12 for attachment to the posts of the lamp support of the automobile and has a lamp socket 13 at about the center of the arc of the front of the casing.

A normally vertical cover 15 is hinged to the casing as at 16 and is held in place on the casing by a spring pressed bolt 17 fitting within a bayonet slot in the rim 19 of the cover 15. The reflector 20 is similar in shape to the casing 10 and has a silvered parabolic reflecting surface 21 and a flat non-reflecting bottom surface 22 slightly indented as at 23 to permit the use of a large size electric bulb when so desired.

The reflector is provided with the usual cord buffer 24 which engages the glass pane 25 in the cover, the reflector being pressed forwardly by its engagement with the curved ring 26 held in place by the springs 27 hooked into lugs 28 at either side of the casing. The portion of the reflector 30 directly behind the bulb 31 is made non-reflecting, preferably by being painted with a dull pea-green paint such as is used on the bottom of the reflector. A small stripe such as 32 may be painted with this pea-green paint, if found necessary, to overcome the effect of the curving of the reflecting surface of the reflector wall as it merges with the casing-engaging flange 33, but if this junction is made sharp there will be no need for the stripe 32 of non-reflecting paint.

To assemble the device the reflector 20 is placed in the casing and pushed rearwardly against the tension of the springs 27, the rear of the reflector engaging the ring 26. The flange 33 of the reflector is provided with notches 35 which permit the passage of small lugs 36 on the casing when the reflector is shifted with respect to the casing and which engage the flange of the casing when the bottom of the reflector is parallel with the bottom of the casing.

The bulb 31 is now inserted and the cover 20 closed by pulling the knob 37 against the force of the spring 38 until the stem 39 enters the short passage of the bayonet slot. Further closing of the cover will now cause the stem 39 to be forced into position by means of the spring 38, thus avoiding the usual pushing and twisting often necessary to get the rim locked on the casing, such pushing and twisting frequently resulting in the breaking of the pane or lens. It is preferable to have the lamps or bulbs 31 of each of the two headlights connected in parallel for running and so arranged that they may be thrown in series when the car is standing, thus dimming the lights in case a parking light is not used.

What we claim is:

In an automobile headlight, a casing having an upper curved portion, a horizontal bottom, and an open front face, a reflector

within said casing and spaced therefrom at top, bottom and rear, a lamp socket on said casing and projecting thru said reflector, a ring surrounding loosely said socket and 5 engaging said reflector, a plurality of supports located on said casing forwardly of said socket, a frame-like front cover to said casing, a pane of glass within said cover, and a spring connecting each support with said ring whereby the reflector is yieldingly held 10 against said pane, and eliminating rattling.

CLYDE F. LANDAHL.
CARLOS H. LANDAHL.
